Textile fabric having improved means providing a unique reflection of light to provide a ribbed effect which is wholly or essentially optical in a fabric having a smooth surface.

UNITED STATES PATENT OFFICE

2,522,225

FABRIC

Alfred L. Helwith, New Rochelle, N. Y.

Application October 18, 1946, Serial No. 704,210

3 Claims. (Cl. 139—426)

1

This invention relates to textile fabrics having ribbed effects.

One object of the invention is to provide a textile fabric having improved means providing a unique reflection of light to provide a ribbed effect which is wholly or essentially optical in a fabric having a smooth surface.

In my Patent No. 1,822,889 for Fabric, issued September 15, 1931, I described a textile having warp yarns of regular and reverse twist arranged in alternate, single succession to provide an optical rib effect transverse to the warp. While this fabric was satisfactory, the principle involved was relatively inflexible or limited in scope and did not lend itself to the production of fabrics having other qualities desired by the trade.

It is therefore an object of the invention to furnish a fabric of improved construction according to the principle involving the use of long and short staple warp yarns arranged in alternate single succession, only one of these yarns requiring a substantial degree of twist.

I have discovered that if a yarn consisting of a short staple, the ends of which provide a fuzzy appearing yarn is disposed in alternate single succession with long staple yarns of substantial twist, such short staple yarn affords such a light effect by reflection or contrast with the adjacent twist surfaces as to furnish a pronounced optical rib transverse to the yarns, where the number of these yarns substantially exceeds the number of yarns at right angles thereto. The short staple yarn may or may not have substantial twist. This invention lends itself to various novel extensions of the principle involved.

Another object of the invention is to provide a fabric of improved construction which is at once durable and soft while utilizing conventional yarns woven on ordinary looms.

Another object of the invention is to furnish an improved inexpensive fabric having the desirable qualities of a cotton textile and possessing a softened appearance and a deep seated luster.

Another object of the invention is the provision of a fabric having a ribbed effect and improved features, affording a soft hand, adapted to drape like wool, and being of especial advantage for the manufacture of men's dress shirts, with outer surfaces of uniform color and

durability. Other objects, features and advantages of the invention will be apparent from the following description of the preferred embodiment, taken in conjunction with the accompanying drawing, in which Fig. 1 is an enlarged view of a piece of fabric embodying the invention; Fig. 2 is a further enlargement illustrating what may be considered to be a modification of the invention; and Fig. 3 is a view of a piece of fabric showing the optical rib effect according to the construction of Figs. 1 and 2.

The advantages of the invention as here outlined are best realized when all of its features and instrumentalities are combined, but useful embodiments may be produced involving less than the whole.

It will be obvious to those skilled in the art to which the invention appertains, that the same may be incorporated in several different constructions. The accompanying drawing, therefore, is submitted merely as showing a preferred exemplification of the invention.

2

shade and perfectly smooth as distinguished from fabrics having mechanical rib formations.

Certain of the above mentioned advantages are best realized by a warp utilizing a short staple yarn made of a material softer than cotton and having a suitable luster, the preferred material being rayon, the yarn of which possess very little twist and affords a substantial number of ends on the short staples used, thus producing a fuzziness partially shielding the luster and at the same time cooperating with the twist surfaces of the long staple, relatively hard cotton or similar material to produce an accentuated optical rib effect transverse to the warp and characterized by a deep seated luster to enhance the appearance of a fabric which is inexpensive while combining the durability and toughness of cotton with the softness of rayon.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claims, and illustrated in the annexed drawing, wherein like parts are designated by the same reference characters throughout the several views.

30 In the drawing:

Figure 1 is an enlarged view of a piece of fabric embodying the invention.

Fig. 2 is a further enlargement illustrating what may be considered to be a modification of the invention.

Fig. 3 is a view of a piece of fabric showing the optical rib effect according to the construction of Figs. 1 and 2.

The advantages of the invention as here outlined are best realized when all of its features and instrumentalities are combined, but useful embodiments may be produced involving less than the whole.

It will be obvious to those skilled in the art to which the invention appertains, that the same may be incorporated in several different constructions. The accompanying drawing, therefore, is submitted merely as showing a preferred exemplification of the invention.

Referring in detail to the drawing, 10 denotes

a fabric embodying the invention and having an interwoven warp and weft, the former illustrated herein as extending horizontally, the fabric being characterized by a ribbed effect 11 extending vertically transversely to the warp. The warp may consist of yarns 12 and 13 of different character arranged in alternate single succession being substantially more closely spaced than the weft yarns 14. For example, there may be approximately 132 warp yarns per inch and approximately 60 filling or weft yarns per inch. The warp yarns 12 may consist of a long staple material having a substantial twist; the material is desirably cotton of which the staple length is approximately 1½ inches, with the twist being preferably standard. By a standard twist is meant the number of twist turns per inch obtained by multiplying 4.75 by the square root of the count of the yarn. By contrast, the warp yarns 13 may consist of a short staple material whose twist may be standard or preferably substantially less and may be so little as to be negligible. By way of illustration, the yarn 13 may be formed of staples between ½ and 1 inch in length; it consists of a material preferably softer than the yarn 12, and while it may be made of silk or suitable qualities of cotton, it consists preferably of rayon having a normal twist of about 4 to 6 per inch. The filling or weft yarns 14 may consist of any suitable material and may be either like the yarn 12 or the yarn 13 and consequently the indication of the twist thereof has been omitted from the drawing. All of the yarns 12, 13, and 14 may be of like weight so that the fabric 10 has absolutely smooth surfaces and all of its yarns may be of uniform shade and color. While the luster of these yarns may also be the same, it is preferable that certain of the warp yarns such as the yarns 13 shall have a luster contrasting with the warp yarns 12. While the latter may be regarded as relatively hard, it is preferred that the yarns 13 shall be relatively soft.

The fabric 10 is characterized in that the yarns 13 possess a fuzzy appearance, this being due to the short staple character thereof, the ends of the staples projecting slightly to form a nap-like finish for these yarns. I have discovered that the fuzzy appearance of the warp yarns 13 has such a light reflecting character with reference to the twist surface of the yarns 12 as to produce a distinctive optical ribbed effect 11 transverse to the warp. In the accomplishment of this effect, the arrangement or angle of the twist is immaterial. Thus the general direction of the twist may be the same in both of the yarns 12 and 13 although I prefer to use opposite twists. For example, the yarn 12 may have a right-hand twist, and the yarn 13 may have a left-hand twist, or the reverse relationship may be employed. The presence or absence of twist, and the direction thereof is wholly immaterial in the filling yarn 14. By reason of the superior strength of regular long staple cotton, I have shown in Fig. 2 a fabric 15 which is exactly like the fabric 10 except that the filling yarn 16 is shown as consisting of a long staple cotton that may in all respects be like the yarn 12 whereby the rib effect is more pronounced.

Heretofore I had discovered that by the employment of warp yarns having regular and reverse twist disposed in alternate single succession, a ribbed effect was produced of purely optical character and which faded out as the number of yarns for each alternation was increased

until eventually a simple and ordinary stripe effect was obtained. According to the present invention I have discovered that by providing a single fuzzy appearing yarn such as 13 between the substantially twisted yarns 12, there is an interplay of light which produces a ribbed effect of an optical character and which is even more accentuated or pronounced than that afforded by my previous fabric. This invention, which I could not foresee from my previous discovery opens up the possibility for many further improvements in fabric construction with corresponding advantages and without increasing the cost of the fabric. Among other things, the 15 sheen of the fabric could be increased by the use of inexpensive rayon which imparted to the fabric as a whole what is known to the trade as a "deep seated luster" and is considered to be highly desirable. The fabric acquired greater 20 softness and a superior feel or "hand"; it lent itself readily to draping and to other purposes for which woolens are used and was especially adapted for use in making men's shirts. At the same time the cotton yarn assured strength and 25 durability to the fabric. Thus new fabrics having important and distinctive advantages can be produced by utilizing well-known or standard yarns woven in a conventional manner and on ordinary looms.

30 However, the invention may also be practised by using short staple yarns 13 of substantial twist, the relatively high twist adding to the strength of the yarn. In that case, the long 35 staple yarn 12 may or may not have a relatively low twist.

I claim:

1. A textile fabric having interwoven warp and weft yarns with the former more closely spaced than the latter, the weft consisting of 40 relatively long staple yarns, the warp consisting of long staple yarns with intermediate short staple yarns arranged in alternate single succession, the latter of these consisting substantially entirely of staples so short as to provide 45 ends sufficient in number to afford a fuzzy surface for such yarns, these short staple yarns being lustrous, and the other warp yarns being twisted and consisting substantially entirely of staples of such substantial length as to produce 50 a non-fuzzy yarn surface contrasting with the surface of the short staple yarns to thus directly produce an optical ribbed effect transverse to the warp with the fabric characterized by a moderate, deep seated lustre afforded by the 55 short staple fuzzy yarn surfaces.

2. A textile fabric having interwoven warp and weft yarns, the warp yarns being more closely spaced than the filling yarns, the warp consisting of long staple cotton yarns with intermediate 60 short staple lustrous spun rayon yarns arranged in alternate single succession, the weft consisting substantially solely of relatively long staple cotton yarns, the cotton warp yarns consisting 65 essentially of long staple cotton having a substantial twist and affording a smooth, relatively hard surface, the rayon warp yarns consisting essentially of rayon staples so short as to afford a multitude of ends sufficient to afford fuzzy relatively soft surface, the surfaces of the cotton and rayon warp yarns cooperating to produce an optical ribbed effect transverse to the warp, with a deep seated luster at the rayon yarns.

3. A textile fabric having an optical ribbed effect comprising yarns forming a warp and weft

of said fabric with the warp more closely spaced than the weft, the weft formed of relatively long staple yarns, the warp formed of long staple yarns of at least 1 1/4 inch staples having a substantial twist and smooth surface and of short staple yarns of substantially 5/8 inch staples having a fuzzy surface of lustrous appearance contrasting with that of said warp long staple yarns, said warp long staple and short staple yarns being arranged in alternate single succession for 10 producing said optical ribbed effect transversely of the warp.
